CLAIM

The ornamental design for a reusable duster refill, as shown and described.

DESCRIPTION

FIG. 1 is a first perspective view of a reusable duster refill showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an enlarged view of the selected portion 9 in FIG. 1;

FIG. 10 is an enlarged view of the selected portion 10 in FIG. 2; and,

FIG. 11 is an enlarged view of the selected portion 11 in FIG. 2.

The dot-dash broken lines in FIGS. 1, 2, 9, 10 and 11 are used to show an area of enlargement and with the broken lines forming no part of the claimed design.

1 Claim, 11 Drawing Sheets
